UNITED STATES PATENT OFFICE.

CHARLES H. AYARS, OF SALEM, NEW JERSEY.

CAN-SOLDERING BLOCK.

SPECIFICATION forming part of Letters Patent No. 417,380, dated December 17, 1889.

Application filed April 12, 1889. Serial No. 306,947. (No model.)

To all whom it may concern:

Be it known that I, CHARLES H. AYARS, a citizen of the United States, residing at Salem, in the county of Salem and State of New Jersey, have invented certain new and useful Improvements in Can-Soldering Blocks and Frames, of which the following is a specification, reference being had therein to the accompanying drawings.

My invention relates to improvements in can-soldering blocks and frames; and the object of my invention is to furnish a can-soldering block and frame which will automatically hold the two edges of the can-cylinder together while being soldered and from which the can-cylinder can be withdrawn after being soldered without the least difficulty.

The old style can-soldering blocks and frames consist of a cylinder the diameter of which corresponds to the diameter of the can to be made and over which the sheet of tin out of which the can-body is to be formed is placed, and a knife which works up and down and which lies along the lap of the can to hold it in place and against which the soldering is done. With this device the can-body has to be forced tightly against the cylinder with the thumbs, and after being soldered there is usually difficulty in withdrawing it, and with heavy tin frequent misfits are made.

In my improvement the cylinder is made in two pieces, the under half being stationary and the upper movable, while the knife is a stationary fixture, but may be adjusted.

In the drawings, Figure 1 is a front elevation of my can-soldering block and frame; and Fig. 2 is a side elevation of Fig. 1, partly in section.

A is a frame, which is bolted to a suitable bench or table.

B is the soldering block or cylinder, which is made in two pieces. The lower piece *a* has cast with it a standard *o*, from which projects a threaded stem *g*, which passes through the frame A, and which is held in place by a nut *j*, and the upper piece *b* is carried on a lever *c*, which is pivoted to the frame A at *d*.

C is a spring placed inside of the cylinder B, one end bearing against the lower half *a* and the other against the lever *c*, which car-

ries the upper half *b* of the said cylinder. This spring passes through the standard *o*, which is bored out, as indicated by dotted lines in the drawings.

m is an offset or guide pivoted to the lever *c* by a bolt *n*. This offset or guide is placed within the upper part of the spring C in order to keep the upper part of the spring in place during the movements of the upper part *b* of the cylinder B.

D is the knife, which is carried by an arm E upon the frame A, and *e* is a screw passing through a slot *f* in the arm E of the frame A and holding the knife D to this arm.

F F are set-screws carried by the frame A and bearing against top of knife D. By means of screws *e* and F the knife may be raised or lowered, so as to adjust it for different thicknesses of metal used in making the cans.

K is a part of the top of the table or bench to which the frame A is bolted.

The operation of the device is as follows: The foot being placed on the treadle H draws down this treadle, the rod G, and lever *c*, which is pivoted at *d*, Fig. 2. The lever *c* carries the upper part *b* of the cylinder B, and when this lever is drawn down the upper part *b* of the cylinder B is moved down against the lower part *a*. The sheet of tin to be formed into the can-body is now placed around the cylinder B, its ends being lapped so as to come under the knife D. The foot being now removed from the treadle H, the expansion of the spring C raises the upper part *b* of the cylinder until it strikes the knife D, the sheet of tin being securely held by the knife and cylinder.

No great care is required in placing the tin upon the cylinder, as the expansion of the cylinder draws the sheet of tin tightly around it and insures a perfect fit.

Upon the top of the cylinder I place a groove *l*, Fig. 1, which allows air to pass between the tin and cylinder and allows the solder to be soaked into the seam better.

After the can-body is soldered the upper part *b* of the cylinder is drawn down and the can-body can be readily removed.

I claim—

1. The combination, in a can-soldering

block and frame, of a stationary knife, a cylinder made in two pieces, the under piece being stationary and the upper piece being carried upon a lever, said lever and a rod, a treadle, and a spring, all substantially as and for the purposes set forth.

2. The combination of the frame A, stationary knife D, with set-screws, as described, stationary part a of cylinder bolted to frame

A, movable part b of cylinder, lever c, spring 10 C, and rod and treadle, all substantially as set forth.

In testimony whereof I affix my signature in the presence of two witnesses.

CHARLES H. AYARS.
